UNITED STATES PATENT OFFICE.

WILLIAM H. CORBETT, OF PORTLAND, OREGON.

HOISTING OR LOGGING DEVICE.

No. 807,109.

Specification of Letters Patent.

Patented Dec. 12, 1905.

Application filed November 4, 1903. Serial No. 179,759.

To all whom it may concern:

Be it known that I, WILLIAM H. CORBETT, a citizen of the United States, residing at Portland, in the county of Multnomah and State 5 of Oregon, have invented new and useful Improvements in Hoisting or Logging Devices, of which the following is a specification.

This invention relates to hoisting or logging devices; and it consists in certain improvements in the construction thereof, as 10 will be hereinafter fully described, and pointed out in the claims.

The invention is illustrated in the accompanying drawings, as follows:

15 Figure 1 shows a section through the device; Fig. 2, an end view; Fig. 3, an alternative construction. Fig. 4 is a section of the screw L and attached parts.

A marks the base of the device, on which 20 the bearing-posts a are mounted. The shaft B is journaled in the bearing a'. The driving-gear C is fixedly mounted on this shaft, preferably between the bearings. The friction-cone c is fixed to rotate with said driving-gear. The drum D is also mounted on the shaft B, and it has the friction-band d for operating on the cone c. The spring E tends 25 to hold the friction-surfaces out of contact. A collar F is arranged on the shaft B against the drum D. A key G extends through the 30 slot b in the shaft B and engages the collar F. The shaft B has an attaching portion B', on which the clutch-actuating mechanism may be arranged outside of the bearing a'. The 35 pin H extends through an opening b' in the end of the shaft and is adapted to communicate the thrust of the actuating mechanism to the drum D through the key G and collar F, the drum D being moved axially on the shaft 40 B to bring the clutch-surfaces into contact. These parts of the mechanism are not new and are shown in my former patent, dated April 15, 1902, No. 697,913.

It is desirable to have some simple mechanism that can be attached to devices of this 45 character already in use and also to make a simple mechanism for devices of this character when finished complete at the shop.

The carrier I is screwed onto the attaching 50 portion B' of the shaft B. A flange-plate I' is bolted to the end of the carrier I. The carrier is in the form of a sleeve, and the flange-plate I' extends beyond the inner face of the sleeve, forming a shoulder i. A nut J is 55 journaled in the flange-plate I'. It has the shoulder j, which is opposed to the shoulder

i. A roller-bearing or rolling bearing-washer is interposed between the shoulders. This washer consists of the disks j', the roller j'', and spreading-ring j'', the latter holding the 60 roller in place. The nut J is internally screw-threaded and is locked against rotation by means of a clamp K, the clamp K having the arm k, which is secured to or abuts against some stationary part of the frame. A screw 65 L operates in the nut J and has the head l provided with means for applying a wrench. A pin l' extends into the socket L' in the end of the screw, as shown in Fig. 4. A hardened screw L' closes the socket L'. As many pins 70 l' as desired may be arranged in the screw. The pin l' abuts a second pin l'', which is carried in the nut, but is free to rotate in the nut. The end of the nut has preferably a cavity J', in which is arranged a roller-bearing washer 75 comprising the disks l'', rollers l'', and spreading-ring l''. The roller-washer abuts the pin H.

In the operation of the device the spring E 80 normally keeps the clutch-surfaces out of engagement. When it is desired to set the clutch, the screw L is turned in. The thrust from the screw is communicated through the pins l'', roller-washer, and pin H to the key G. The counter thrust of the nut comes on 85 the shoulder i and the friction between the shoulders i and j is relieved by the roller-washer heretofore described.

The pins in themselves reduce very materially the friction in that they form different 90 points of movement, so that the movement on each one is quite slow as compared with that of the shaft. I prefer, however, to have not only the pins, but also the roller-washer, as shown. A reverse action of the screw releases 95 the clutch, the spring moving the drum on the shaft to accomplish this purpose. The clamp K holds the nut in a stationary position, so that the screw can be readily operated to set the clutch or to release the clutch. 100 The disk j', roller j'', and spreading-ring j'' are the same in construction as similar parts marked j'', j'', and j''. (Shown in enlarged view in Fig. 3.) In the alternative construction (shown in Fig. 3) the roller-washer formed with 105 the disk l'' is omitted and the relief from excessive frictional resistance is accomplished through the thrust-pins alone. In it the nut J'' has the shoulder j'', which opposes the shoulder i. A roller-bearing washer is interposed 110 between the shoulders, said washer comprising the disks i'', rollers j'', and spreading-

ring j^7 . The pin l' in the end of the screw engages a pin l^6 , which is journaled in the nut, and this acts directly upon the pin H .

It is desirable to do away with side thrust 5 on the bearing. This is accomplished by this device, the bearing carrying the drum being entirely free from side thrust. By making the thrust-screw hollow and placing pins in the socket so formed the device is made very 10 compact. Where only the thrust-pins are used, there is some danger of their heating. In the preferred construction this is entirely obviated.

What I claim as new is—

- 15 1. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices 20 in the attaching end of the shaft, extending from without the bearing to within the bearing; and a connection between said thrust devices and the one of the friction-wheels free to move axially into engagement; 25 of an apparatus mounted on the attaching portion of the shaft for actuating said thrust devices comprising a carrier attached to the shaft; a relatively fixed screw member mounted on the carrier, the carrier being arranged to receive the axial thrust of said screw member; means for locking said relatively fixed screw member from rotating with the carrier; an active screw member operating in connection with the relatively fixed screw member and adapted to exert a thrust on said thrust devices. 30
- 35 2. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices 40 in the attaching end of the shaft, extending from without the bearing to within the bearing; and a connection between said thrust devices and the one of the friction-wheels free to move axially into engagement.

- 45 3. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices 50 in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a carrier attached to the shaft; a relatively fixed screw member mounted on the carrier, the carrier being arranged to receive the axial thrust of said screw member; means for locking said relatively fixed screw member from rotating with the carrier; an active screw member operating in connection with the relatively fixed screw member and adapted to exert a thrust on said thrust devices. 55
- 60 4. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices 65 in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a carrier attached to the shaft; a relatively fixed screw member mounted on the carrier, the carrier being arranged to receive the axial thrust of said screw member; means for locking said relatively fixed screw member from rotating with the carrier; an active screw member operating in connection with the relatively fixed screw member and adapted to exert a thrust on said thrust devices; a roller-bearing between the relatively fixed screw member and the carrier; and a roller-bearing interposed between the active screw member and the thrust devices. 70
- 65 5. In a hoisting or logging device the combination with the main bearings; the shaft 75

80 with the relatively fixed screw member and adapted to exert a thrust on said thrust devices; and a roller-bearing between said relatively fixed screw member and the carrier.

3. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a carrier attached to the shaft; a relatively fixed screw member mounted on the carrier, the carrier being arranged to receive the axial thrust of said screw member; means for locking said relatively fixed screw member from rotating with the carrier; an active screw member operating in connection with the relatively fixed screw member and adapted to exert a thrust on said thrust devices; and a roller-bearing interposed between the active screw member and the thrust devices. 85

4. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a carrier attached to the shaft; a relatively fixed screw member mounted on the carrier, the carrier being arranged to receive the axial thrust of said screw member; means for locking said relatively fixed screw member from rotating with the carrier; an active screw member operating in connection with the relatively fixed screw member and adapted to exert a thrust on said thrust devices; a roller-bearing between the relatively fixed screw member and the carrier; and a roller-bearing interposed between the active screw member and the thrust devices. 90

5. In a hoisting or logging device the combination with the main bearings; the shaft 95

journaled in said bearings and having an attaching end; a driving friction-wheel mounted on said shaft; a drum mounted on said shaft; a driven friction-wheel locked against 5 rotation relatively to said drum, said driving and driven friction-wheels being adapted to be brought into frictional engagement by an axial movement of one of them; thrusting devices in the attaching end of the shaft, extending from without the bearing to within the bearing; a connection between said thrust devices and the one of the friction-wheels free to move axially into engagement; of an apparatus mounted on the attaching portion of the shaft 10 for actuating said thrust devices comprising a carrier attached to the shaft; a relatively fixed screw member mounted on the carrier, the carrier being arranged to receive the axial thrust of said screw member; means for locking said relatively fixed screw member from rotating with the carrier; an active screw member operating in connection with the relatively fixed screw member and adapted to exert a thrust on said thrust devices; and a loose 15 pin interposed between said active screw and said thrust devices.

6. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum said driving and driven friction-wheels being adapted to be brought into frictional engagement by an axial movement of one of them; thrusting devices in the attaching end of the shaft, extending from without the bearing to within the bearing; a connection between said thrust devices and the one of the friction-wheels free to move axially into engagement; of an apparatus mounted on the attaching portion of the shaft 20 for actuating said thrust devices comprising a sleeve-shaped carrier having an internally-flanged shoulder; a nut having an external shoulder opposed to the shoulder on the flange; and a screw in the nut adapted to exert thrust on said thrust devices.

6. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a sleeve-shaped carrier having an internally-flanged shoulder; a nut having an external shoulder opposed to the shoulder on the flange; a screw in the nut adapted to exert thrust on said thrust devices; and a roller-bearing interposed between the internally-flanged shoulder on the carrier, and the external shoulder on the nut.

6. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; a connection between said thrust devices and the one of the friction-wheels free to move axially into engagement; of an apparatus mounted on the attaching portion of the shaft for actuating said thrust devices comprising a carrier attached to the end of the shaft having an internal flanged shoulder; a nut having an opposing shoulder and journaled in the flanged end of the carrier, said nut having a cavity; a roller-bearing washer arranged in said cavity; and a screw in said nut arranged to exert force on said thrust devices, the roller-bearing washer being interposed between the screw and said devices.

7. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum said driving and driven friction-wheels being adapted to be brought

into frictional engagement by an axial movement of one of them; thrusting devices in the attaching end of the shaft, extending from without the bearing to within the bearing; a connection between said thrust devices and the one of the friction-wheels free to move axially into engagement; of an apparatus mounted on the attaching portion of the shaft for actuating said thrust devices comprising a sleeve-shaped carrier having an internally-flanged shoulder; a nut having an external shoulder opposed to the shoulder on the flange; and a screw in the nut adapted to exert thrust on said thrust devices.

8. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum said driving and driven friction-wheels being adapted to be brought into frictional engagement by an axial movement of one of them; thrusting devices in the attaching end of the shaft, extending from without the bearing to within the bearing; a connection between said thrust devices and the one of the friction-wheels free to move axially into engagement; of an apparatus mounted on the attaching portion of the shaft for actuating said thrust devices comprising a sleeve-shaped carrier having an internally-flanged shoulder; a nut having an external shoulder opposed to the shoulder on the flange; a screw in the nut adapted to exert thrust on said thrust devices; and a roller-bearing interposed between the internally-flanged shoulder on the carrier, and the external shoulder on the nut.

9. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; a connection between said thrust devices and the one of the friction-wheels free to move axially into engagement; of an apparatus mounted on the attaching portion of the shaft for actuating said thrust devices comprising a sleeve-shaped carrier attached to the end of the shaft having an internal flanged shoulder; a nut having an opposing shoulder and journaled in the flanged end of the carrier, said nut having a cavity; a roller-bearing washer arranged in said cavity; and a screw in said nut arranged to exert force on said thrust devices, the roller-bearing washer being interposed between the screw and said devices.

10. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a sleeve-shaped carrier attached to the end of the shaft having an internally-flanged shoulder; a nut having an opposing shoulder journaled in the flanged end of the carrier, said nut having a cavity; a roller-bearing washer arranged in said cavity; and a screw in said nut arranged to exert force on said thrust devices, the roller-bearing washer being interposed between the screw and said devices; and a roller-bearing between the shoulder on the nut and the internal flanged shoulder on the carrier.
11. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising the carrier I secured on the end of the shaft and having the flanged plate I' forming the shoulder i; the nut J journaled in the flange-plate and having the shoulder j opposing the shoulder i said nut also having a cavity J', at its inner end; a roller-bearing interposed between the shoulders j and i; the screw L arranged in the nut; means for locking the nut J from rotating with the carrier; a roller-bearing washer arranged in the cavity of the nut; said roller-bearing washer being arranged to act upon said thrust devices; and a loose pin arranged between the screw and washer.
12. In a hoisting or logging device the combination with the main bearings; the shaft journaled in said bearings and having an attaching end; a driving friction-wheel mounted on said shaft; a drum mounted on said shaft; a driven friction-wheel locked against rotation relatively to said drum, said driving and driven friction-wheels being adapted to be brought into frictional engagement by an axial movement of one of them; thrusting devices in the attaching end of the shaft, extending from without the bearing to within the bearing; and a connection between said thrust devices and the one of the friction-wheels free to move axially into engagement; of an apparatus mounted on the attaching portion of the shaft for actuating said thrust devices comprising a screw member fixed against axial movement relatively to the shaft, said screw member being mounted outside of the bearing, the shaft being free to rotate without rotating the screw member; and an active screw member arranged to operate with said relatively fixed screw member for exerting thrust on the thrust devices.
- In testimony whereof I have hereunto set my hand in the presence of two subscribing witnesses.
